US0D1013459S

(12) **United States Design Patent** (10) **Patent No.:** **US D1,013,459 S**
(45) **Date of Patent:** **** Feb. 6, 2024**

(54) **CONTAINER**

(71) Applicant: **Mepal B.V.**, Lochem (NL)

(72) Inventor: **Simon van Es**, Hengelo (NL)

(73) Assignee: **MEPAL B.V.**, Lochem (NL)

(**) Term: **15 Years**

(21) Appl. No.: **29/740,733**

(22) Filed: **Jul. 7, 2020**

(30) **Foreign Application Priority Data**

May 14, 2020 (WO) 94892

(51) **LOC (14) Cl.** **09-07**

(52) **U.S. Cl.**

USPC **D7/629; D9/425**

(58) **Field of Classification Search**

USPC D9/414-416, 424-425, 430-432,
D9/759-761; D7/500, 542-543, 550.1.

(57) **CLAIM**

The ornamental design for a container, as shown and described.

DESCRIPTION

FIG. 1 is a perspective view of the container with the lid open showing my new design;

FIG. 2 is another perspective view with the lid closed;

FIG. 3 is a front view thereof;

FIG. 4 is a back view thereof;

FIG. 5 is a right side view thereof;

FIG. 6 is a left side view thereof;

FIG. 7 is a top view thereof;

FIG. 8 is a bottom view thereof;

FIG. 9 is a perspective view of an alternative embodiment of the container with open lid showing my new design;

FIG. 10 is another perspective view with the lid closed,

FIG. 11 is a front view thereof;

FIG. 12 is a back view thereof;

FIG. 13 is a right side view thereof;

FIG. 14 is a left side view thereof;

FIG. 15 is a top view thereof; and,

FIG. 16 is a bottom view thereof.

The broken lines and the areas within the broken lines represent portions of the container and form no part of the claimed design.

1 Claim, 16 Drawing Sheets
